UNITED STATES PATENT OFFICE.

OTTO S. BEYER, OF CARLSTADT, NEW JERSEY, ASSIGNOR TO E. W. BLISS COMPANY, OF BROOKLYN, NEW YORK, A CORPORATION OF WEST VIRGINIA.

CAN-SEAMING MACHINE.

No. 800,424.

Specification of Letters Patent.

Patented Sept. 26, 1905.

Application filed May 3, 1902. Serial No. 105,846.

To all whom it may concern:

Be it known that I, OTTO S. BEYER, a citizen of the United States, residing at Carlstadt, in the county of Bergen and State of New Jersey, have invented certain new and useful Improvements in Can-Seaming Machines, of which the following is a specification.

This invention relates to machines for making the seams for joining the heads or ends of cans to the bodies thereof.

It relates especially to a machine for double-seaming the heads of round or cylindrical cans.

Figure 1 of the accompanying drawings is a side elevation of the machine. Fig. 2 is a rear elevation. Fig. 3 is a front view in section on the line 3 3 in Fig. 1, showing the machine in operation. Fig. 4 is a horizontal section, on a larger scale, cut generally in the plane of the line 4 4 in Fig. 1 and showing the machine in operation. Fig. 5 is a vertical section on the line 5 5 in Fig. 4, the parts being shown in the position of rest. Fig. 6 is a sectional elevation of the secondary seamer and its carrier. Fig. 7 is a sectional elevation of the can-clamp-operating cam and its lever. Fig. 8 is a fragmentary sectional front view of the frame, showing means for mounting the seamer-carriers. Fig. 9 is a plan of the delivery-table.

The improved machine is of that character wherein the can-body having its head placed upon it is transferred by hand or otherwise into position on a rotatable disk or pad, which is thereupon elevated to bring the can-head into engagement with a continuously and rapidly revolving chuck, the disk and chuck together serving as a clamp to hold the can during the seaming operation. By the continued operation of the mechanism a seamer, preferably in the form of a seaming-roll, is protruded and caused to bear upon the flange of the cover to curl it inward and downward beneath the flange of the can and to force both flanges inward toward the can-body. Thereupon a second seamer, preferably also a seaming-roll, is caused to engage the can-head and acts to flatten and compress the double seam against the can-head, which is firmly supported by the chuck. After the two seamers have receded the can-clamp opens to release the can, preferably by the descent of the disk or pad, whereupon the can is removed and re-

placed by another to be operated on. The mechanism for operating the seamers and for controlling the operation of the can-clamp is preferably started by the operator, who moves a treadle or other lever for that purpose, and after the series of operations necessary to complete the head of one can these parts preferably come to rest, although the invention does not exclude a continuous operation of these mechanisms.

Referring to the drawings, let A designate any suitable framework for supporting the working parts. In the construction shown this frame is provided with bearings in which turns a counter-shaft B, having fast and loose pulleys B', driven from any suitable shaft, and also pulleys B² and B³, the latter preferably a stepped or cone pulley. The upper part of the frame is provided with bearings for a vertical shaft C, designed to be driven at high speed, having a pulley C' fixed on it which is driven from the pulley B² by means of a belt α passing over loose pulleys C² C³. On the lower end of the shaft C is fixed the can-head chuck D, forming the upper disk of the clamp, by which the can is held during operation. The lower disk of this clamp is a rotatable pad E, mounted on a shaft F, which is stepped in a suitable bearing in a vertically-movable slide G, which slides in a bearing G' on the frame A. The slide G carries a table H on its upper end, preferably through arms h. The slide G is elevated to bring the pad E into operative position in order to clamp the can α between it and the chuck D, as shown in Fig. 3. The slide may be variably operated; but in the construction shown it is operated both by the starting-treadle and by a holding and dropping cam.

J is the starting-treadle, which is shown as a lever fixed on a shaft b, turning in the frame and having an arm b', connected by a rod c to an arm d on a rock-shaft K, arranged horizontally in transverse bearings in the frame A just back of the bearing G'. On the projecting ends of the shaft K are mounted arms e e, to which are connected links f f, the lower ends of which are pivoted to a vertically-movable head L, engaging the slide G. The head L might be fixed to the slide; but as a convenient means of introducing a yielding medium I prefer to have it slide relatively to the slide G and be connected thereto by

means of springs $L' L'$, as best shown in Fig. 3. These springs are shown as compression-springs confined between the head L and a flange or collar G^2 , which is fixed to the slide G , being preferably a set-collar which can be adjusted thereon to varying heights. The springs are shown as encircling rods or bolts g , which pass down through the head L and have on their lower ends adjusting stop-nuts g' , adapted to limit the expansion of the springs. It results from this construction that on pressing down the treadle J motion is communicated through the rod c , arm d , shaft K , arms $e e$, and links $f f$ to raise the head L , which, moving upward, compresses the springs L' , whereby the pressure of these springs is made effective to raise the slide G until the can placed upon the pad E is forced up against the chuck D , whereupon the further movement of the treadle and head L is taken up by compression of the springs L' . To provide an adjustment between the treadle J and head L , the arm d is made adjustable relatively to the shaft K , so that this shaft, with the arms $e e$ keyed to it, may be turned to bring the head to any desired height and then fastened to the arm d in any suitable manner, as by a set-screw. To this end the arm d is formed on a hub or sleeve d' , mounted loosely on the shaft K and having an arm d^2 adjacent to one of the arms e and formed with an arc-shaped slot through which a set-screw e' passes to fasten the two arms together.

35 The frame A is provided with a rearward extension A' , which may be in a separate piece bolted to it, as shown, and this rearward extension or bracket provides bearings for two horizontal shafts, the one a worm-shaft M , extending from front to rear and hence parallel with the shaft B , and the other a cam-shaft P , extending transversely. The worm-shaft M is driven from the shaft B by a belt a' engaging one of the cone-pulleys B^3 and a corresponding pulley M' on the shaft M . The shaft M has a worm M^2 , which drives a worm-wheel P^2 , turning loosely on the shaft P , whereby this shaft when clutched to the worm-wheel is driven at a relatively slow speed. The shaft P carries three cams P' , P^3 , and P^4 , which operate, respectively, the can-clamp and the first and second seamers.

To relieve the operator of the necessity of holding the treadle depressed in order to keep the can-clamp properly engaged upon the can during a seaming operation, I provide means whereby when the treadle is once depressed mechanism is brought into action for holding the clamp closed upon the can until the end of the operation and then opening the clamp to release the can, or, in other words, for holding the slide G elevated and then mechanically lowering it at the proper time. This is the function of the clamp-holding cam P' , (see Fig. 7,) which has a notch 10,

which in its position of rest receives a roller 11 on the upper arm of a rock-lever Q , the lower arm of which is connected by a rod Q' to an arm Q^3 , fixed on the shaft K . The pressing down of the treadle J acts to clutch the cam-shaft P to its driving worm-wheel P^2 by any suitable one-revolution clutch, whereupon the shaft P begins to revolve. The same movement of the treadle in raising the slide G rocks the lever Q , so as to remove the roller 11 from the notch 10 of the cam P' . As soon as this cam begins to revolve its notch passes beyond the roller and its concentric peripheral portion bears upon the roller, thereby preventing the return movement of the lever K and through the connected parts preventing the descent of the slide G . Hence the cam P' acts to hold the slide G elevated until the cam has executed one revolution, whereupon (the operator having previously released the treadle) the roller 11 falls back into the notch 10 and thereby, through the connected parts, lowers the slide G and releases the can, this operation being completed just as the shaft P , being unclutched from its driving-wheel P^2 , comes to rest. For the adjustment of the exact relation between the cam P' and roller 11, on the one hand, and the slide G , on the other, any one of the intervening parts may be made adjustable. Preferably the connecting-rod Q' is made adjustable in length, as shown.

The one-revolution clutch referred to is located at R to couple the shaft P to the wheel P^2 . As clutches of this character are well known and as the particular construction of clutch is unessential to my invention, I have not illustrated the clutch in detail. Suffice it to say that the clutch is controlled by a lever R' , operated from the treadle J or any other starting-lever or movable part. In the construction shown the lever R' is operated by a tappet-rod R^2 , the lower end of which is connected to an arm R^3 , fixed on the rock-shaft K . When the treadle is depressed, the rod R^2 is pulled downward and engages the lever R' , which it tilts down, so that the upper arm of the lever causes the clutch to engage. At the end of one revolution of the shaft P the clutch is caused to disengage itself in any of the known ways, or it may be forced to disengage by the motion communicated from the cam P' to the lever Q and connected parts to the rock-shaft K , whereby the tappet-rod R^2 is pushed upward, so that the lever R' is restored to its original position, thereby releasing the clutch.

In Fig. 1, S designates the seamer, which usually and preferably is constructed as a seaming-roll. The machine may have only one seamer; but for double-seaming two seamers are required, as shown in plan Fig. 4, where the first is lettered S' and the second S^2 . These seamers are mounted on slides or carriers (lettered, respectively, $T' T^2$) movable

horizontally in direction from front to rear through a slideway or guide-box i , fastened in the main frame A , which is shaped to inclose this box, as shown in Fig. 8. At their rear ends the slides carry rollers 13 and 14, respectively, Fig. 4, which bear against the cams $P^3 P^4$, respectively. For better guidance the rear portions of the slides work through slideways in a projection 15 on the bracket A' . As the cam-shaft P rotates the cam P^3 first acts to push forward the slide T' to cause the first seamer S' to act. At about the end of its operation the cam P^4 pushes forward the slide T^2 , carrying the second seamer S^2 to cause this seamer to act. As the second seamer is pushed forward the first seamer is retracted, and finally toward the end of the revolution of the shaft the second seamer is retracted. The retraction of the slides and seamers might be accomplished by suitable engagement with the cams P^3 or P^4 or other cams in any way known to mechanics; but I prefer to retract them by springs, for which purpose each slide T' or T^2 is provided with a projection 16, which receives the pressure of a spring 17, Fig. 5, partly housed in a recess in the upper part of the projection 15. Preferably a screw-stud 18 projects through a hole in the projection 16 and serves as a guide for the spring which encircles it.

The seamers may be given any relative or actual movements desirable for performing any given class of work, and to this end the cams $P^3 P^4$ may be varied or substituted, as occasion may demand. For ordinary can-seaming, however, it is preferable that the first seamer shall advance gradually, so as to gradually turn the flange of the can-head which is rotated against it, the seamer finally remaining stationary for somewhat over one revolution. Thereupon the second seamer, being advanced, should engage the can and roll down the seam during one or more revolutions. In the particular construction shown the first seamer acts during about ten revolutions and the second seamer during the following three or four revolutions. The relative conformation of cams $P^3 P^4$, by which this result is attained, is apparent from Fig. 5, where the cam P^3 is shown in full lines and the cam P^4 partly in dotted lines, both being shown in the stationary or inactive position.

It is practically desirable that the first seamer shall be unyieldingly supported, while at the same time it is important that the second seamer shall be supported in yielding manner, so that it may compensate for varying thicknesses of metal and so that the necessity for extremely nice adjustment may be avoided. It is also desirable that both seamers shall be mounted adjustably, so that they may be set forward or back, so as to accommodate different-sized cans. To this latter end both the slides $T' T^2$ are made in two sections which are relatively adjustable. This

is clearly apparent from Fig. 6, which shows the slide or carrier T^2 detached. Each slide has accordingly a front section 19, which is the part that slides through the box i and the projecting front end of which carries the seamer-roll, and a rear section 20, which works in the guide 15 and carries the cam-roller 13 or 14. These two sections are connected by means of a screw, whereby they may be adjusted. For the slide T' this screw 21 (see Fig. 5) is preferably right and left threaded and engages right and left female threads in the sections 19 and 20, having a nut 23 pinned to it, by means of which it can be turned, and having set-nuts 24, 24, which when the slide is extended are set against the sections 19 and 20, respectively. The screw for the slide T^2 is marked 22 (see Fig. 6) and screws into the section 19 thereof, having also a nut 23 pinned thereon by which to turn it and a set-nut 24. Its other end passes through a thimble 25, which is screwed into the section 20, and the screw is headed within the thimble, its head receiving the pressure of a stiff spring 26, housed in a socket in said section 20. This spring is stiff enough to keep the head pressed normally firmly against the thimble 25, so that the slide holds the seamer S^2 to its work until it meets a resistance exceeding the stress of the spring, whereupon the spring is compressed so that the seamer yields.

For seaming any given size of cans the can-clamp comprising the chuck D and disk or pad E must be shaped to conform to the size and outline of the respective ends of the can, the chuck D , as usual, entering within the recess in the upper head, while the lower disk is shaped to engage and center the lower end of the can. The slide G , carrying the disk E and table H , is to be set to such height that when lifted it will elevate the can into engagement with the chuck D and in addition will compress the springs L' to any desired extent. This adjustment is made by loosening the set-screw of the set-collar G^2 and moving the slide G up or down within it to the desired height and thereupon retightening the set-screw. The seamers $S' S^2$ are to be set forward or backward to adapt them to the precise diameter of the can to be seamed. To insure the correct engagement of the seamers with the flange on the can-head, the chuck D is made vertically adjustable by means of a screw j , Figs. 1 and 2, screwing through a cross-head k and engaging the upper end of the shaft C , by which to raise or lower this shaft. The precise mode of its engagement is not important, but may be made with a head j' , as shown in dotted lines in Fig. 2, engaged within a cap l , screwed upon the upper end of the shaft.

In operation the can-body, with its head placed upon it, is set upon the disk E . The operator then presses down the treadle J , which, as described, lifts the slide G , thereby elevating the can until its upper end is pressed

firmly against the chuck D, which is rapidly revolving. The same operation starts the cam-shaft P, which executes one revolution, the first effect of which is through the cam P' and lever Q to hold the slide G pressed up. 5 Immediately thereafter the cam P' moves the seamer S' forward and causes it to gradually turn in the flange on the head and curl it under that on the body, and thereupon to turn 10 in both flanges, whereupon the first seamer recedes, and the second seamer having meanwhile advanced engages the can and rolls the seam down flat. Thereupon the second seamer recedes and the cam P' releases the roller 15 of the lever Q, permitting the roller to enter its notch, and thereby to lower the slide G, which descends to its original position, and finally the cam-shaft P, having completed one revolution, comes to rest. The operator then 20 pushes the seamed can out of the way, usually by the same movement by which he advances the next can into place to be seamed.

It is desirable to quickly dispose of the cans which have been seamed, and to this 25 end I utilize the whirling motion that they retain after being discharged from the can-clamp to insure their being forcibly thrown beyond the machine. To accomplish this, the table H is made with an elevated wall or up- 30 turned flange m at one side, preferably the rear, so that as the can x is pushed off the disk E it engages this wall, and by reason of its spinning motion in the direction of the arrows in Fig. 9 it is caused to roll along the 35 wall, and thereby acquires a considerable impetus in the direction of the arrow x', whereby it is thrown out to the left of the machine and to a suitable distance to be clear thereof. It is found that the spinning motion causes 40 the can to travel back toward the wall m; but if under any circumstances it is found that this is not its tendency the operator can easily give it a slight obliquely-backward push, which will accomplish this result.

45 My invention is susceptible of considerable modification without departing from its essential features. Many of the features of construction and arrangement which I have described, although desirable and convenient, 50 are by no means essential and may be greatly varied or departed from. For example, while the arrangement of the main driving-shaft or counter-shaft B with bearings in the main frame and near the base thereof is desirable, 55 various other arrangements may readily be substituted. Also for securing the high speed of the chuck D, which is preferably about twelve hundred revolutions per minute, and the low speed of the cam-shaft P, preferably 60 about sixty revolutions per minute, the driving of the former directly by a belt from the main shaft B, while the latter is driven through a worm, is a convenient and desirable construction, but may readily be substituted

by other means of driving. The mounting 55 of the table H on the same support as the freely-rotating disk or pad E is not essential, but is adopted for convenience and simplicity. The interposition of the rock-shaft K and its connections for communicating motion between the treadle or operating lever J, the rising-and-falling slide G, the can-clamp-holding cam P', and the clutch-operating lever K' is also a convenient, compact, and desirable means, but is not essential, and may be substituted by other mechanical connections. The carrying of the seamers upon slides arranged to move in straight lines at the rear of the can being seamed is a simple, convenient, and desirable arrangement whereby these 80 parts are compactly housed and out of the way, although readily enough accessible; but other arrangements for suitably carrying the seamers and communicating to them the motion imparted by the cams may be substituted. Other means for providing the desirable 85 adjustments may be substituted. The arrangement of the operating-lever J near the floor as a treadle is preferable, but the lever may be otherwise arranged.

90 What I claim is—

1. The combination with a can-clamp comprising a rotating chuck and disk, of a vertically-movable slide connected to the disk, means for lifting said slide including a horizontal rock-shaft K having an arm connected to said slide, a lever having an adjustable connection with said shaft, and a movable member connected with said lever and adapted to be displaced to move the latter.

100 2. In a can-seaming machine, the combination with a rotary can-clamp, of two slides each comprising a bar adapted to be moved lengthwise, a slideway through which said bars move, the latter being arranged side by side in said slideway, seamers mounted upon and supported solely by said bars, and rotating cams adapted to engage the rear portions of said slides and move them toward the can to cause said seamers to act upon the latter.

110 3. In a can-seaming machine, the combination with a rotary can-clamp, of a seamer, a slide carrying said seamer, and a rotating can arranged to act against the rear end of said slide to push it forward and cause the seamer 115 to act upon the can, a slideway through which said slide works, and a spring adapted to be compressed between said slide and slideway as the former advances, whereby the slide is pushed back after each advance movement, 120 said slideway being formed with a socket adapted to receive said spring.

125 4. In a can-seaming machine, a seamer, a slide carrying the same, and a cam for operating said slide, the slide constructed in two reversely-screw-threaded sections, a screw connecting them having reverse threads, whereby the slide can be adjusted in length,

by rotation of the screw, and means for holding the parts when adjusted.

5. In a can-seaming machine, a seamer, a slide carrying the same, and a cam for operating said slide, the slide constructed in two sections relatively movable, one of which is formed with a socket, a spring confined therein, a rod having a headed end in said socket bearing against said spring, and a thimble 10 surrounding said rod and screwed to said section, said rod connected to the other of said sections.

6. In a can-seaming machine, the combination with a can-chuck, of two seamers, movable parts carrying them, and mechanism for moving said parts adapted to first advance the first seamer slowly to act upon the can to turn in the flanges thereof, and before the first seamer is retracted to advance the second 20 seamer into engagement with the can, then to retract the first seamer, and after the second seamer has rolled down the seam, to retract the second seamer.

7. In a can-seaming machine, the combination of two seamers, movable parts carrying them, and cams acting against said parts for advancing the seamers, adapted to first advance the first seamer, and subsequently to advance the second seamer, and after the latter is advanced to retract the first, and finally to retract the second.

8. In a can-seaming machine, the combination of two seamers, longitudinally-movable slides carrying them, and cams acting against the ends of said slides to move them, the slide carrying the primary seamer being adapted to rigidly communicate the thrust of the cam to said seamer, and the slide carrying the secondary seamer being formed in two parts, and 40 a spring confined in one of said parts and reacting against the other, whereby to yieldingly communicate the thrust of the cam to said seamer, whereby the primary seamer acts unyieldingly to turn the flanges, and the secondary seamer acts yieldingly to roll down the seam.

9. In a can-seaming machine, the combination of two seamers, parallel slides carrying them, cams acting against the ends of said 50 slides to move them longitudinally toward the can, and a slide-box held in the frame of the

machine opposite the can, and forming a slideway for said slides.

10. In a can-seaming machine, the combination of an upright frame having an opening through it, a slide-box projecting transversely through said opening, and fastened therein, and a slide carrying a seamer and movable within said slide-box, whereby said box forms a slideway for said slide. 55 60

11. In a can-seaming machine, the combination of an upright frame having an opening through it, a slide-box placed in said opening, a set-screw for fastening said slide-box therein, and a slide movable in said slide-box. 65

12. In a can-seaming machine, the combination of an upright frame having a rectangular opening through it, a slide-box fitting and fastened in said opening, said slide-box formed with sides and a bottom, and having a removable top, and a seamer-carrying slide movable in said slide-box. 70

13. In a can-seaming machine, the combination of a standard having a horizontal opening through it, a rotary can-clamp opposite said opening, parallel slides passing through said opening and having seamers at one end, and cams carried by said standard on the side opposite said can-clamp, and adapted to coat with said slides to cause the seamers to advance and retreat. 75 80

14. In a can-seaming machine, the combination with a rotary can-clamp, of a table having a wall against which the rotating can when released from the clamp may bear, whereby 85 to cause the can to be projected out of the machine.

15. In a can-seaming machine, the combination of a can-clamp comprising a rotating chuck and a relatively movable rotative disk, 90 a slide carrying said disk, and a table carried by said slide having a wall against which the rotating can when released from the clamp may bear, whereby to cause the can to travel horizontally out of the machine. 95

In witness whereof I have hereunto signed my name in the presence of two subscribing witnesses.

OTTO S. BEYER.
